US00D682420S

(12) **United States Design Patent**
Abram et al.

(10) **Patent No.:** **US D682,420 S**
(45) **Date of Patent:** **** May 14, 2013**

(54) **TOP SHEET OF AN INCONTINENCE PAD**

(75) Inventors: **Carlitheia R. Abram**, Ardmore, PA (US); **Jehann Biggs**, Philadelphia, PA (US); **Maria Gustin Bergström**, Hälsö (SE); **Anita Haraldsson Hedbratt**, Mölnlycke (SE)

(73) Assignee: **SCA Hygiene Products AB**, Göteborg (SE)

(**) Term: **14 Years**

(21) Appl. No.: **29/354,153**

(22) Filed: **Jan. 20, 2010**

(30) **Foreign Application Priority Data**

Aug. 20, 2009 (EM) 001161707

(51) **LOC (9) Cl.** **24-04**

(52) **U.S. Cl.**

USPC **D24/124**

(57) **CLAIM**

The ornamental design for a top sheet of an incontinence pad, as shown and described.

DESCRIPTION

The sole FIGURE is a top plan view of a top sheet of an incontinence pad, showing our new design.

The inner broken line perimeter represents the boundary of the claimed design, and the outermost perimeter depicts a portion of the top sheet of an incontinence pad that forms no part of the claimed design. The broken lines form no part of the claimed design.

1 Claim, 1 Drawing Sheet
